UNITED STATES PATENT OFFICE

HUGH F. RIPPEY, OF SEATTLE, WASHINGTON, ASSIGNOR TO LAUCKS LABORATORIES INC., OF SEATTLE, WASHINGTON, A CORPORATION OF WASHINGTON

EDIBLE NUT AND PROCESS OF PROVIDING THE SAME

No Drawing.

Application filed August 4, 1927. Serial No. 210,721.

My invention relates to a nut as a new article of manufacture and to the process of providing the same. More particularly, my invention relates to a nut characterized by 5 having the outer layer of the shell enveloping the kernel removed.

For purposes of clearness of description I will describe my invention as applied to that type of nuts known as English walnuts, but 10 it is to be understood that my invention is not to be limited to any such specific application but extends to all fields presenting similar problems and conditions.

Heretofore, it has been the custom to bleach 15 the shells of whole walnuts after the husk is removed in order that the walnuts when marketed may have a bright, attractive, and pleasing appearance. Unbleached walnuts, in general, are dark in color, spotted, more 20 or less dirty, and unattractive. This bleaching has been accomplished in general by a chemical means such as bleaching by means of gases, by washing, or immersing in a bath of bleaching solution such as hypochlorites and 25 compounds having a similar action. Such chemical bleaching by means of washing and immersion has been unsatisfactory because the nuts do not bleach evenly and consequently their color is not uniform, and it is particu- 30 larly unsatisfactory because the solution frequently seeps through into the nut, through tiny openings in the shell particularly at the blossom end and such solutions are extremely injurious to the walnut meats, causing them 35 to become rancid, to mold, have a bad taste, and even to become slightly poisonous. A substantial percentage of loss results from this injuring of the kernel.

The primary object of my invention is to 40 provide a nut, the outer layer of the shell of which has been mechanically removed to the desired depth, without in any way affecting the meat or kernel of the nut, so that all stains and discolorations are removed, and 45 there results a nut characterized by having a smooth, bright, uniformly colored shell of attractive and natural appearance, i. e. one having the natural surface lines or fissured markings of the nut preserved or retained, 50 while having exposed the natural color of

the shell fiber uniformly as the color of the nut. A further primary object of my invention is to provide a nut having all stains and discolorations removed without in any wise injuring the kernel within. A further pri- 55

mary object of my invention is to remove the outer layer portion of that shell of the nut which directly envelopes the kernel, and leave only such portion of the shell as may be readily cracked; that is, my purpose is providing 60 a nut having a so-called "paper" shell, even though said nut when grown may have a very hard, thick, shell; and a final primary purpose of my invention is providing a product having the characteristics above set forth, 65 and is particularly characterized by its cheapness of production,—such product being one which must be capable of production on a large scale.

I have discovered that by removing the 70 outer layer of the walnut shell all discolorations are removed and walnuts so treated have a uniform color and an attractive, pleasing appearance, becoming thereby more desirable and more readily marketable. I have success- 75 fully removed the outer layer of the walnut shells by means of a sand-blast. Such sand-blast is applied in such a manner that approxi- mately the whole natural surface of each wal- 80 nut comes in contact with the force of the sand-blast and minute particles of the shell are thereby uniformly removed producing and exposing an entirely new surface for each shell. This new surface has been found to be of a light color, pleasing, smooth, attrac- 85 tive in appearance and the uniformity of the coloration is such as to be of great advantage in marketing the product in competition with chemically bleached walnuts.

In addition to the above advantages it is 90 quite evident that there can be no damage to the walnut meat as a result of this treatment of the shell and that the desired effect and the desired product, namely a uniformly light colored, clean, smooth surface and attrac- 95 tive walnut is secured without the loss and damage entailed by the use of chemical bleach. This product may be produced by other mechanical means than by the use of sand-blast, as for example by rapidly revolv- 100

ing steel brushes. I have found however that sand-blasting of the walnut produces not only uniformity of color but may be accomplished conveniently and rapidly and is therefore, according to my present experience, a preferred means of producing the product.

An important advantage of my invention is that the product may be produced more cheaply than chemically bleached walnuts may be produced, without any of the disadvantages of the chemical bleach which have been enumerated above and which are well known to the trade.

I have further discovered that I may take the heavy shelled walnut and by proper adjustment of the force of the sand-blast and of the duration of time of exposure of the nut to the sand-blast, or of the size of the sand particles, I can regulate or reduce the thickness of the shell of the finished walnut so that I may produce walnuts similar to and in all respect the equal of the so called "paper shell" walnut of commerce without in any way impairing the quality of the walnut meat within the shell and at the same time producing, as herein above described, a walnut of attractive, pleasing color, and appearance.

I have found that I can satisfactorily and cheaply reduce the thickness of the shells of hard shell almonds producing the equivalent of so called "paper shell" almonds in so far as the ease of cracking said shells is concerned. Also the same treatment applied to hickory nuts, pecans, and other nut results in products more readily usable, more attractive and more readily saleable than the nuts in their natural and unprocessed state.

By way of summary and in general, it will be noted that the nut of my invention is: (1) characterized by being mechanically treated so that no possible injury can result to the meat within, that is the kernel by reason of any chemical bleaching solution entering through the shell, especially the blossom end; (2) characterized by a mode of treatment which cuts away or removes an appreciable layer or portion of the nut; (3) characterized by a mode of treatment which in no wise alters or affects the natural color of the nut fiber, that is my method as a minimum result of its application removes to such an extent the outer portion of the shell as to expose the natural color of the inner shell fiber and is directly opposed to chemical treatment methods which are admittedly designed to employ chemical agents to bleach the nuts—such portion as is originally clean being acted upon by the chemicals for just as long a period as the stained portion of the nut shell,—a process obviously unavoidably certain to result in a lack of uniformity of color, or at least an artificial or imparted color to the nut,—the latter fact being especially true when the bleaching process is applied by methods adapted to handle large quantities of nuts; and (4)

is characterized by leaving unimpaired the natural appearance of the nut, that is its surface lines or fissured markings are preserved despite the cutting away or removal of the outer portion of the shell, a property or feature which is important as the nut to command the highest price should look like a nut according to present custom.

I claim:

1. As a new article of manufacture, a nut characterized by having the outer portion of its shell removed to such an extent as to expose the inner natural color of the shell fiber uniformly as the color of the nut.

2. As a new article of manufacture, a nut characterized by having the outer portion of its shell removed to such an extent as to expose the inner natural color of the shell fiber uniformly as the color of the nut, and by having its natural appearance as to surface lines or fissured markings preserved.

3. As a new article of manufacture, a walnut characterized by having the outer portion of its shell removed to such an extent as to expose the inner natural color of the shell fiber uniformly as the color of the nut.

4. As a new article of manufacture, a walnut characterized by having the outer portion of its shell removed to such an extent as to expose the inner natural color of the shell fiber uniformly as the color of the nut, and by having its natural appearance as to surface lines or fissured markings preserved.

5. The process of preparing nuts which comprises mechanically removing the outer portion of the shell coating surrounding the kernel to such an extent as to expose the color of the shell fiber as the color of the nut.

6. The process of preparing walnuts which comprises mechanically removing the outer portion of the shell coating surrounding the kernel to such an extent as to expose the color of the shell fiber as the color of the nut.

7. The process of preparing nuts which comprises removing by a sand blast the outer portion of the shell coating surrounding the kernel to such an extent as to expose the color of the shell fiber as the color of the nut.

8. The process of preparing walnuts which comprises removing by a sand blast the outer portion of the shell coating surrounding the kernel to such an extent as to expose the color of the shell fiber as the color of the nut.

9. The process of preparing nuts which comprises mechanically removing the outer portion of the shell coating surrounding the kernel to such an extent as to expose the natural color of the shell fiber while maintaining the surface lines or fissured markings substantially normal.

10. The process of preparing walnuts which comprises mechanically removing the outer portion of the shell coating surround-

ing the kernel to such an extent as to expose the natural color of the shell fiber while maintaining the surface lines or fissured markings substantially normal.

5 11. The process of preparing nuts which comprises removing by a sand blast the outer portion of the shell coating surrounding the kernel to such an extent as to expose the natural color of the shell fiber while maintaining the surface lines or fissured markings substantially normal.

10 12. The process of preparing walnuts which comprises removing by a sand blast the outer portion of the shell coating surrounding the kernel to such an extent as to expose the natural color of the shell fiber while maintaining the surface lines or fissured markings substantially normal.

15 In witness whereof, I hereunto subscribe
20 my name this 30 day of July, A. D. 1927.

HUGH F. RIPPEY.
